GENERATOR HOOK-UP

Henry J. Mastenbrook, Cleveland, Ohio, assignor
to The Swartwout Company, Cleveland, Ohio, a
Corporation of Ohio

Application December 21, 1929
Serial No. 415,715

18 Claims. (Cl. 122—451.2)

This invention relates to pressure generators and more particularly to an improved hook-up for generators of the general class described and claimed in the United States patent to Copley, No. 1,193,125, issued August 1st, 1916.

In the operation of steam boilers and other power plant equipment such as steam traps and the like, it is frequently desirable to actuate diaphragm type valves by fluid pressure which varies with variations in the liquid level in a container. Copley discloses a pressure generator adapted to span the water level of a container and to generate a pressure which varies with the water level.

It is among the objects of my invention to provide apparatus for connecting a pressure generator of the general type disclosed by Copley to a boiler or the like which will permit the generator to be raised or lowered either with or without tilting its longitudinal axis and without disconnecting the generator conduit from the container; to provide a generator hook-up whereby the hot water in the generator may be blown down without blowing out the cool water in the conduit below the generator; to provide a generator hook-up which is easily adjusted, which may be blown down without interfering with its efficient operation except during the actual blowing down operation, and which is of rugged and efficient design.

The above and other objects of my invention will appear from the following description of a preferred form of my generator hook-up, reference being had to the accompanying drawing in which:

Fig. 1 is an end elevation of the generator hook-up applied to the end of a steam boiler drum; and Fig. 2 is a side elevation of the apparatus illustrated in Fig. 1.

The operation of the generator in my present invention is substantially the same as the generator of the Copley patent referred to above and will be but briefly described herein. The twin generators 1 and 2 are supported by the section 3 of the conduit which spans the boiler water level L—L. The twin generators 1 and 2 are made up of the inner pipes 4 and 5 which are connected at their upper and lower ends to the conduit section 3, tubular shell portions 6, and radiating fins 7. The shell portions 6 surround the pipes 4 and 5 and contain a volatile fluid such as water.

When the generators are in the position illustrated and the boiler is in operation the pipes 4 and 5 will contain water up to the boiler water level and steam above this level.

As the boiler water level varies, the level in the

pipes 4 and 5 will vary correspondingly and the volatile fluid within the shells 6 will be heated to a degree depending on the water level in the pipes 4 and 5. Thus the pressure generated by the volatile fluid will vary with the boiler water level. The shells 6 are connected at their lower ends by a tube 8 and a pressure conducting tube 9 may lead from the shells 6 to the diaphragm chamber 10 of a feed water valve or the like.

As best seen in Fig. 1, the pipes 4 and 5 are bent into downwardly extending U-shaped portions 11 below the generators 7. The object of this construction is to prevent internal circulation of hot water in the generators. In generators not equipped with these drop leg sections the steam which condensers in the conduit 3 forms a column of hot water which will eventually fill the conduit 3 down to the lower connections of the inner generator pipes and then pass outwardly into the generators. As the difference in temperature between the steam and water in the generators is a vital factor in their efficient operation this flow of hot water into the generators is undesirable. By providing the U-shaped pipe portions 11, the hot condensate which forms in the conduit 3 cannot displace the cool water in the downwardly extended U-shaped pipes 11 and the operation of the generators will not be affected by hot condensate rising into the generators.

The upper end of conduit section 3 is connected to the lower end of the upper conduit section 12 by a shorter pipe 13 in which is interposed a union 14. This union 14 may be of any desired and suitable type and its purpose is to allow relative swinging movement between the conduit sections 3 and 12. When the union 14 is loosened the conduit sections may be moved relative to each other. When the union 14 is tightened the conduit sections will be held in the desired position and a rigid pressure tight connection will be secured.

A shut-off valve 15 at the upper end of the conduit section 12 provides means for shutting off the conduit and generators from the upper part of the boiler drum 16. A pipe 17 connects the valve 15 to the boiler 16 and has interposed in its length 100 a union 18 which is similar to the union 14 and has a similar function in that it provides an adjustable connection between the conduit section 12 and the boiler drum 16.

At the lower end of the conduit section 3 is a T-connection to which is attached the blow down pipe 19 and the connecting pipe 20. Included in the pipe 20 is a union 21. The cooler conduit 22 is connected to the end of the pipe 20 and the union 21 permits easy variation of the angle be-

105

110

tween the generator conduit section 3 and the cooler section 22.

The cooler section 22 may consist of an enlarged tubular portion 23 having radiating fins 24 as shown in Fig. 1. The object of this cooler is to cool the hot boiler water before it enters the generators 1 and 2 so that the difference in temperature between the steam in the upper parts of the generators and the water in the lower parts will be great enough to give the proper pressure generating action.

An adjustable connection between the cooler section 22 and the lower conduit section 25 is provided by the short pipe 26 and the union 27 in the same manner as above described in regard to the connections between the other conduit sections. The end of section 25 is connected to a shut-off valve 28 which is attached to the boiler drum 1 by a pipe 29 and union 30 in the same way as the upper conduit 12. The valve 28 permits the conduit to be shut off from the lower part of the boiler when desired.

The generator blow down valve 31 is placed in the blow-down pipe 19 below the T-connection. This valve may be of any suitable type, the one illustrated being an ordinary hand-operated valve, and is normally kept closed during the operation of the boiler. When, however, air becomes entrapped in the generators or they become filled with scale, etc., it is desirable to blow them out. This is done by closing the valve 28 and opening the valve 31, permitting steam to blow through the generators and thoroughly clean them. As the cooler 23 is lower than the point where the conduit 22 joins the conduit 3, the cool water in the cooler and the lower part of the conduit system will not be discharged. When the blow-down valve 31 is closed and the shut-off valve 28 opened at the completion of the blow down operation, the cool water from the cooler 24 will rise to boiler level in the conduit 3 and the inner pipes 4 and 5 of generators 1 and 2 and the generators will immediately be ready for operation.

In the above description and the drawing it will be seen that my generator hook-up provides means for connecting generators of the class described to boilers and the like so that their vertical position and the angle of their axis may be readily varied to suit different conditions. I have also provided a hook-up in which the generators can be quickly and easily blown down without disturbing the cool water in the cooler. Although I have illustrated and described but one form of my invention, it will be clear to those skilled in the art that modifications may be made without departing from the spirit of my invention. I do not, therefore, wish to be limited in any manner other than by the claims appended hereto.

60 I claim:

1. A generator hook-up for boilers comprising a section of conduit swivelly connected to a boiler above the water level, a section of conduit swivelly connected to said first section and having a pressure generator mounted thereon, a section of conduit swivelly connected to said second section and inclined downwardly with respect thereto having a cooler associated therewith, a section of conduit swivelly connected at one end to said third section and at the other end to the boiler, a discharge valve between said second and third sections and shut-off valves at the ends of said conduit adjacent the boiler.

2. A generator hook-up comprising a sectional conduit connected to span the liquid level of a

liquid container, a generator on said conduit, swivel means for connecting the sections of said conduit, said sections being swingable to allow said generator to be moved vertically without changing its angular relation to the horizontal and a blow-down valve at the lower end of said generator.

3. A generator conduit comprising a plurality of pivotally connected sections, a generator on one of said sections, a cooler on the section adjacent and below said generator section, said two last mentioned sections being connected together at adjacent ends, said last mentioned section being inclined downwardly with respect to the generator section, a section pivotally connecting the generator section to a liquid container, a section pivotally connecting the cooler section to the liquid container, a blow-down valve between said generator and said cooler and a shut-off valve between said last named conduit section and said liquid container.

4. In a pressure generator hook-up the combination of a conduit comprising at least four pivotally connected sections adapted to be connected to a liquid container and spanning the liquid level in the same, a generator comprising an inner pipe and outer shell, means for connecting the upper end of said inner pipe to one section of said conduit, means including a drop leg pipe section for connecting the lower end of said inner pipe to said conduit section, and a cooler on a conduit section below the generator carrying conduit section, said cooler and the section on which it is mounted being inclined downwardly with respect to the section with which said generator is associated, a generator blow down valve between said generator and cooler, and a shut off valve in one of said sections and disposed between said cooler and the liquid container, the pivotal mounting of said sections permitting vertical adjustment of the position of the generator without changing its horizontal position.

5. In a pressure generator hook-up the combination of a conduit comprising at least four pivotally connected sections, a generator comprising an inner pipe and an outer shell, means for connecting the upper end of said inner pipe to one section of said conduit, means including a drop leg pipe section for connecting the lower end of said inner pipe to said conduit section, a cooler on a conduit section below the generator carrying conduit section and being inclined downwardly with respect to said generator carrying conduit section and a generator blow-down valve between said generator and said cooler, and a shut-off valve in one of said sections and disposed adjacent the end of said cooler remote from said generator, the pivotal mounting of said sections permitting vertical adjustment of the position of the generator without changing its horizontal position.

6. The combination with a boiler, of a sectional conduit comprising pivotally connected sections spanning the water level of the boiler, a generator mounted on one of said sections, a cooler associated with another of said sections, the upper end of the section having the cooler associated therewith being connected to the lower end of the section having said generator associated therewith and being disposed entirely below said last mentioned section, said generator being movable vertically without changing its angular relation to the horizontal.

7. In a pressure generator hook-up the combination of a fluid conduit comprising at least four

- pivottally connected sections, a generator comprising an inner pipe and outer shell, means for connecting the upper end of said inner pipe to one section of said conduit, means including a 5 drop leg pipe section for connecting the lower end of said inner pipe to said conduit section, and a cooler on a conduit section below the generator carrying conduit section, said cooler and the section on which it is mounted being inclined down- 10 wardly with respect to the section with which said generator is associated, a generator blow down valve between said generator and cooler, and a shut-off valve in one of said sections associated with said cooler and disposed between said cooler 15 and the liquid container, the pivotal mounting of said sections permitting vertical adjustment of the generator without changing its angular position.
8. A generator hook-up for a boiler comprising 20 a section of conduit swivelly connected to a boiler above the water level, a section of conduit swivelly connected to said first section and having a pressure generator mounted thereon and having a blow-down valve at the lower end thereof, 25 whereby the generator line may be opened to pass a scavenging flow of steam through the generator, a section of conduit swivelly connected to said section and inclined downwardly with respect thereto and having a cooler associated 30 therewith, a section of conduit swivelly connected at one end to said third section and at the other end to the boiler, a shut-off valve at the end of said last named section adjacent the boiler adapted to be closed when said blow-down valve 35 is opened to allow steam to pass through said second named section of pipe and said generator without disturbing the water in the cooler which may thereafter be allowed to rise in the generator.
- 40 9. A method of scavenging a pressure generator of the class described and restoring the same to a condition substantially the same as that existing previous to the scavenging operation which consists in passing a scavenging flow of steam 45 through the generator, isolating a volume of cooling fluid in a portion of the generator line and permitting the fluid to rise in the generator at the termination of the scavenging operation.
10. In combination with a boiler, a pressure 50 generator, means for mounting said generator on said boiler so that said generator may be adjusted vertically without changing the angular relation thereof with respect to the horizontal, said means comprising a plurality of sections 55 swivelly connected and relatively movable one with respect to the other, certain of said sections being swivelly connected to the boiler.
11. In combination with a boiler, a generator 60 mounted to span the water level thereof and being adjustable vertically without changing the angular relation thereof with respect to the horizontal, means for mounting said generator on said boiler, said means being pivotally connected to said boiler and being rotatable in a plane normal to the water level, said means forming a part of a fluid conduit spanning the normal water level of the boiler.
12. In combination with a boiler, a generator 70 hook-up comprising a section of conduit swivelly connected to the boiler at a point above the water level and in fluidic communication therewith, a second section of conduit open at one end swivelly connected to the first section of conduit 75 and in fluidic communication therewith, said second section having a pressure gen-
- erator mounted thereon spanning the normal water level of the boiler, and a valve at the lower end thereof for controlling the passage of fluid traversing the generator through the open end of the conduit section, a third conduit swivelly connected to said second conduit and in fluidic communication therewith and inclined downwardly with respect thereto and in fluidic communication therewith, said last named pipe section having a cooler associated therewith, a 80 fourth conduit swivelly connected to the last named conduit and in fluidic communication therewith and swivelly connected to the boiler below the normal water level and in fluidic communication therewith, said pipe sections being 85 adjustable to varying angular position without substantially changing the positional relation between the generator and cooler or the angular position of the generator with respect to the normal water level in the boiler, said last named pipe section having valve means for precluding the passage of fluid in the cooler through the outlet when the valve in the second conduit is opened to pass fluid through the generator.
13. A method of blowing down a pressure generator of the class described and restoring the same to a condition substantially the same as that existing previous to the blowing down operation which consists in passing a volume of fluid 90 through the generator, isolating a volume of fluid from the boiler and the generator and passing the fluid thus isolated to the generator after the blowing down operation.
14. In a pressure generator hook-up, the combination of a conduit comprising at least four 100 pivotally connected sections, a generator comprising an inner pipe and an outer shell, means for connecting the upper end of the inner pipe to one section of the conduit, and means including a drop leg pipe section for connecting the lower end of the inner pipe to the conduit, the pivotal mounting of said sections permitting vertical adjustment of the generator without disturbing the angular position thereof to the horizontal.
15. In a generator hook-up the combination of 110 a sectional conduit connected to span the liquid level of a container, a pressure generator, means for connecting the upper end of said generator to said conduit, means including a drop leg pipe section for connecting the lower end of said generator to said conduit, said sectional conduit being comprised of a plurality of sections pivotally connected together in such a manner as to permit said generator and drop leg pipe section to be moved vertically upon pivotal adjustment of said 115 sections without changing the angular relation of said generator and drop leg to the horizontal.
16. A generator hook-up for boilers comprising a sectional conduit swivelly connected to a boiler above and below the water level, said conduit 120 comprising four swivelly connected sections including an intermediate pair of sections, a pressure generator mounted on one of said intermediate sections, a cooler mounted on another section of said conduit, a discharge valve in said 125 conduit between said generator and said cooler, and shut-off valves at the ends of said conduit sections without changing the angular relation of said generator and drop leg to the horizontal.
17. A generator hook-up comprising a sectional 130 conduit connected to span the liquid level of a container for steam and water, said conduit having four sections comprising an outer pair swingable with relation to the container and an inner pair pivotally connected to said outer sections and to each other, and a pressure generator mounted 135
18. A generator hook-up comprising a sectional 140 conduit connected to span the liquid level of a container for steam and water, said conduit having four sections comprising an outer pair swingable with relation to the container and an inner pair pivotally connected to said outer sections and to each other, and a pressure generator mounted 145
19. A generator hook-up comprising a sectional 150 conduit connected to span the liquid level of a container for steam and water, said conduit having four sections comprising an outer pair swingable with relation to the container and an inner pair pivotally connected to said outer sections and to each other, and a pressure generator mounted

on one of said sections in said inner pair, said sections being swingable to allow said generator to be moved vertically without changing its angular relation to the horizontal, and to allow said generator to be angularly adjusted with relation to the horizontal without changing its vertical position.

18. A generator hook-up comprising a sectional conduit connected to span the liquid level of a 10 container for water and steam, comprising an

outer pair of sections swingably mounted with respect to the container, an inner pair of sections pivotally connected to said outer sections and to each other, a pressure generator mounted on one of said sections in said inner pair and a cooler 80 mounted on an adjacent section of said conduit, said sections being swingable to allow said generator to be moved vertically without changing its angular relation to the horizontal.
